[57] **ABSTRACT**

A method of making precious metal postage stamps which can be very finely worked in intricate designs without creating any cracks or holes in the metal. The method includes the steps of laminating a precious metal sheet in a plurality of different rolling-mills, manually beating the laminated sheet with a hammer, this beating being carried out such that one or more hammers are moved along a trapezoidal path during the beating operation, coating one side of the sheet with an adhesive agent and forming a relief design in the sheet.

3 Claims, No Drawings

METHOD OF MAKING A PRECIOUS METAL POSTAGE STAMP

CROSS REFERENCE TO RELATED APPLICATION

This is a continuation-in-part application of co-pending U.S. application Ser. No. 246,524, Madeleine Boccard, filed Apr. 24, 1972, now abandoned.

BACKGROUND OF THE INVENTION

1. Field of the Invention

The present invention concerns a method of manufacturing a postage stamp in precious metal, particularly gold, silver or platinum.

2. Description of the Prior Art

Certain processes for manufacturing postage stamps in precious metals have previously been used. In known processes, however, there is a serious problem in that holes or cracks commonly occur in the stamps. In the known processes the very thin sheets of precious metal lose their flexibility and become very brittle. Actual breakage of the stamp is often the result.

SUMMARY OF THE INVENTION

The present invention proposes a method of manufacture of an unbreakable postage stamp of extreme flexibility. Stamps produced according to the method of the invention can be very finely worked with an intricate design without any cracks or holes appearing in the metal. The method by which this is accomplished includes the steps of alternately laminating sheets of precious metal in different rolling-mills and hand beating the laminated sheets with one or more hammers. This beating is carried out in a trapezoidal pattern, i.e., one or more hammers are moved along a trapezoidal path during the manual beating operation. This manner of beating influences the structure of the sheet giving it great flexibility. The processed sheets, which may vary in thickness from between 0.05 mm to 0.20 mm, are then coated with glue, stamped out and divided into stamps of a predetermined size.

DETAILED DESCRIPTION

In the process of the present invention bars or slabs of precious metal, e.g., gold, are transformed into fine sheets. To do this, machines for laminating precious metal are used. In themselves, however, existing machines are unsuitable in the field of precious metal postage stamp production, since such machines do not confer to the metal sheets the extreme flexibility, which is necessary. It is for this reason that manual labor is used to give the sheets of precious metal their essential flexibility.

The procedure described hereafter specifies a sheet of gold, however the same method can be applied to other precious metals such as platinum and silver.

To an ingot of pure gold are added copper, nickel and silver in proportions calculated to give the desired stamp color; e.g., pale yellow, lemon color, pale green, dark green, etc. The mixture is heated to 1200° C or 1300° C and a new ingot is made which will measure, for example, 15 cm in length, 35 cm in width and 0.7 cm or 0.8 cm in thickness. After re-heating, the ingot is passed through a first rolling mill, is heated again to effect softening and is then laminated a second time. The ribbon of gold lengthens by 4 to 6 meters each time it goes through the rolling mill and the process is con-

tinued until the ribbon is 17 to 18 meters long. The metal ribbon is then folded into 16 equal parts and fed into a third rolling mill which cuts it up into squares measuring 10 cm on each side. Cut into four pieces, the sheets of gold are placed one at a time between the pages of some sort of notebook. The relative thickness of the sheet, measured in lengths of milimeters is sufficient to allow it to be rough-rolled into squares of 10 cm by 10 cm.

10 From this stage on, machines can no longer be used. Instead, the sheets of gold are hand beaten with one or more hammers to give the required flexibility. Preferably, a plurality of hammers weighing 3,250 kg, 6,500 kg and 9 kg, respectively, are used to beat the sheets of gold. After each beating operation the gold is alternately heated, beaten again, and heated again. During the beating process the workman places the gold on a flat granite slab. The strokes of the hammer must be carefully applied with the desired force in a wedge shape or, more precisely, in a trapezoidal pattern (i.e., in the form of a swallow's tail). This type of beating produces a molecular arrangement in the metal resulting in the exact structure necessary for excellent flexibility. Thus, the metal sheets will be suitable for making postage stamps.

In the foregoing description of the beating operation, it is to be understood that the expressions "wedge shape" and "trapezoidal pattern" do not refer to the shape of the indentations left by each hammer stroke.

30 Rather, these terms refer to the fact that the beating is carried out such that the hammers are moved along a trapezoidal path during the beating operation. For example, the beating may first be carried out in a direction corresponding to a parallel side of a trapezoid. The beating then continues in a direction corresponding to one of the inclined sides of the trapezoid and thence, in a direction corresponding to the other parallel side. Finally, the beating is carried out in the direction of the 40 other inclined side, whereupon the starting point will be reached.

45 The gold sheets thus obtained vary in thickness between 0.05 mm and 0.20 mm. The gold beater works the sheet once more before it undergoes the stamping process which gives it its final aspect. The stamping which, for example, may produce a design in relief causes tensions in the metal, and this is the reason why it is extremely important that the metal be very flexible and pliable in order to avoid cracking or breaking. 50 Heretofore it has not been possible to attain the proper metal characteristics by practicable, known methods.

55 Applicant has discovered, however, that by using the abovedescribed beating process the problems experienced in known methods of precious metal stamp production are overcome. Specifically, the above described beating process alters the structure of the precious metal sheets such that a detailed relief design can be applied thereto without the formation of cracks or small holes.

60 If the formation of the final, relief design is carried out (by, for example, coining, pressing or deep embossing) after the lamination step and without the abovedescribed beating process, small holes or cracks in the stamp will result. This is so because, after lamination, the sheet of precious metal is subject to numerous internal stresses, and it exhibits uneven thicknesses and a lack of flexibility. As such, the sheet is not adapted

to sustain an additional operation which would create substantial new stresses.

The applicant has discovered that the above described process of manually beating the metal in a trapezoidal pattern is particularly effective in relieving the stresses and in producing a precious metal sheet which is uniform and flexible. The resulting sheet, then, is ideally suited for a final coining or embossing step which can be performed without the usual formation of cracks and/or holes.

When the sheets of gold, silver or platinum have attained the correct thickness and flexibility, they are then coated with glue. This glue is applied from a sheet of gummed paper with the result that the reverse side of the metal is adhesive in exactly the same manner as an ordinary paper postage stamp.

Next, the sheet is stamped either into single stamps or into a block of several stamps. All that remains to be carried out is the perforation, the number of perforations being indicated by the customer. The edges of each stamp may also be turned back in a roof-like slope.

Postage stamps made of precious metal are used on various occasions, for example to mark an anniversary of an important event. In particular, it is common to issue postage stamps made of precious metal in honor

of distinguished individuals or in commemoration of the anniversaries or dates of independence of certain countries.

What is claimed:

5 1. A method of making a postage stamp of precious metal comprising the steps of:

- a. laminating the precious metal in rolling mills to form a precious metal sheet;
- b. manually beating the precious metal sheet with a hammer, the beating being carried out such that the hammer is moved along a trapezoidal path during the beating;
- c. coating one side of the precious metal sheet with an adhesive agent; and
- d. forming a relief design in the precious metal sheet.

2. A method as defined in claim 1 wherein the precious metal sheet is cut into a plurality of postage stamps after formation of the relief design.

3. A method as defined in claim 1 wherein:

- a. the beating step is carried out more than once; and
- b. the laminated sheet is heated after each beating step.
